UNITED STATES PATENT OFFICE.

HENRY B. COOLEY, OF NEW BRITAIN, CONNECTICUT, ASSIGNOR TO THE AMERICAN PAPER GOODS COMPANY, OF MONTCLAIR, NEW JERSEY, A CORPORATION OF NEW JERSEY.

DRINKING-CUP-STERILIZING MACHINE.

1,174,692.

Specification of Letters Patent. Patented Mar. 7, 1916.

Application filed February 27, 1912. Serial No. 630,291.

To all whom it may concern:

Be it known that I, HENRY B. COOLEY, a citizen of the United States, and a resident of New Britain, in the county of Hartford 5 and State of Connecticut, have invented a new and Improved Drinking-Cup-Sterilizing Machine, of which the following is a specification.

My invention relates to the class of machines above mentioned, and an object of 10 my invention, among others, is to provide a machine by means of which drinking cups may be thoroughly sterilized in the process of manufacture and for immediate packing 15 and to produce durable cups with strong, secure and smooth seams and that are perfectly water tight and sanitary.

A form of machine embodying the invention and in the construction and use of 20 which the objects above set out, as well as others, may be attained is illustrated in the accompanying drawings, in which—

Figure 1 is a side view of a portion of a machine embodying my invention with parts 25 cut away to show construction. Fig. 2 is a view of the machine in front elevation with parts broken away to show construction and with parts of the folding mechanism shown in Fig. 1 removed.

30 In the accompanying drawings the numeral 5 denotes the frame of my improved machine that may be of any suitable form and composed of any proper material. Upon this frame are supported devices for 35 folding the blanks and for forming the joints. This mechanism may be of any desired construction, the machine herein illustrated including a gumming roll 6 with the supporting roll 7 co-acting therewith, and 40 to which the blanks are supplied by mechanism of any satisfactory construction. It may be briefly stated that in the machine herein shown the blanks are presented folded crosswise at about the center to the 45 gumming rolls by which gum is applied to the opposite projecting edges of the lower ply of each blank after which the blanks are delivered to further folding mechanism including an upper feed roll 8 and a lower 50 feed roll 9. These rolls are so constructed that the blank will pause in its travel for a sufficient length of time to enable the projecting edge of the lower ply of each blank to be folded over the edge of the upper ply 55 and caused to adhere to the upper surface

of said upper ply. This operation is performed as by folder blades 10 suitably mounted and operated in connection with a forming plate 11 mounted on a rock shaft 12 and operated as by means of an arm 13 60 and rod 14. From the folding device above described the folded blanks are delivered to feed rolls 15.

Further and detailed description of the folding mechanism is deemed unnecessary 65 herein and reference is hereby made to my co-pending application filed January 29th, 1912, of S. No. 673,959 for such understanding as may be further desired regarding this mechanism.

70 Feed belts 16—17 are carried upon belt supports 18—19 suitably mounted in the frame of the machine and in such position that the blanks are delivered from the feed rolls 15 to and between said belts. The 75 large belt roll 20 is so located that the blanks will be delivered therefrom into the throat between the presser roll 21 and heating cylinder 22, which travel closely together, the pressure being regulated as by means of adjusting screws 23 engaged with the bearings of the roll in any suitable manner. A shallow tank 35 is formed in the throat between said roll and cylinder as by means of flanges 24 on each end of the roll closely fitting 80 against the ends of the cylinder, the surfaces of the roll and cylinder forming the sides of the tank as plainly shown in Fig. 1 of the drawings.

85 A reservoir 25 for paraffin is mounted 90 on the frame of the machine from which a trough 26 delivers to the tank just above described, a valve 27 being employed to regulate the flow of paraffin to the tank. This reservoir and the cylinder 22 are 95 heated in any desired manner, as herein shown steam being conveyed through a pipe 28 to the reservoir 25, this steam passing through a steam jacket around the reservoir and being conveyed through a connection 29 to the cylinder 22, this connection being made in any well known manner to permit rotation of the cylinder, and as plainly shown at the other end of the cylinder in Fig. 2 where the connection 30 is 100 105 with a pipe 31 delivering to a cylinder 33 that together with a presser roll 32 constitutes another set of devices for acting upon the blank in a manner to be hereinafter described. From the cylinder 33 the steam 110

passes through a discharge pipe 34. These cylinders and rolls and in fact all of the parts hereinbefore described may be rotated in any suitable manner, and the cylinder 33 and roll 32 are rotated to pass blanks to counting mechanism to be hereinafter described, the blanks falling through space from between the cylinder 22 and the roll 21. Each of the presser rolls 21 and 32 10 are covered with some yielding material 36, as felt, by means of which substantially all flow of paraffin is prevented between the cylinder 22 and roll 21 as the folded blanks 37 pass therebetween. Adjusting screws 38 15 are employed to regulate the tension between the cylinder 33 and roll 32.

Receptacles 39 are located underneath the ends of the roll 32 and cylinder 33 to receive paraffin that may flow over the ends 20 of the tank between the roll 21 and cylinder 22 dripping on to flanges on the ends of the roll 32 and thence into the receptacles, spouts 40 conveying paraffin from the receptacles 39. A receiver 41 is rotatably 25 mounted in position to receive the blanks 37 from the roll and cylinder 32-33, this receiver having compartments 42 formed by pins 43, the receiver being rotated as by means of a pawl 44 mounted on an arm 45 30 pivoted on the shaft 46 of the receiver and acting in connection with a ratchet 47 secured to said shaft or to the receiver. The arm 45 is actuated by a rod 48 pivotally connected with an actuating slide 49 35 mounted upon the shaft 50 of a toothed counter 51. This toothed counter 51 has a circular flange 52 projecting from one side, with openings 53 through said flange, in the device shown two openings located 40 on diametrically opposite sides being employed and the counter having fifty teeth. These openings are formed to receive a lug 54 on the slide, and a spring 55 holds the slide with the lug normally against the 45 flange.

A counter arm 56 mounted on the shaft 50 of the toothed counter and carrying at one end a counter pawl 58 is connected at the opposite end by a rod 59 with a counter 50 cam 60 mounted on a cam shaft 61, this cam shaft also having secured thereto an actuating slide operating cam 62, located to strike a roll 63 on a slide rod 64.

While I have shown and described herein 55 two sets of presser rolls and heating cylinders, these sets may be varied in number to any degree, and the means for driving the several parts not herein specifically shown will suggest themselves to the ordinary mechanic, and for this reason detailed 60 description and illustration of such parts have been omitted.

In the normal operation of the device the delivery of paraffin through the trough 65 26 will be so regulated that the tank par-

tially formed by the flanges 24 will be kept filled with melted paraffin to the required amount, this delivery trough being located to deliver the paraffin on to the joints of the blanks that pass from between the belts 16-17 into said tank and through the paraffin with which they are thoroughly coated. The folded blanks are then pressed between the presser roll 21 and the heating cylinder 22, the latter serving to thoroughly 75 heat said blanks.

The mucilage applied by the mucilage roll 6 is, by the action of this heating cylinder, thoroughly softened, and the pressure between the cylinder and roll upon the 80 joint or seam presses the folds firmly in contact and causes the mucilage to exert its full adhesive qualities in securing the joint. The joint, as the blank passes through the box containing the paraffin, is completely 85 sealed and this compression of the heated joint together with the heated paraffin and mucilage insures a strong and water tight joint sufficient to thoroughly withstand the use to which the cups are intended to be 90 put.

The blanks as they pass between the rolls and heated cylinder are thoroughly pressed, the mucilage is softened and uniformly spread to form a smooth joint, and the 95 paraffin is uniformly spread over the entire blank, completely covering the joint, both the mucilage and paraffin being condensed with a result that a thoroughly sterilized cup is produced having a firm and water tight joint 100 and covered with a uniform layer of paraffin. The layer of paraffin and the heat to which the blank is subjected thoroughly sterilize it, and the finished cup is not required to be handled, the entire operation, after the 105 blanks are placed in the machine to be acted upon by the folding mechanism, being mechanically performed.

It is essential that the paraffin shall not be burned, as this would be particularly objectionable in a drinking cup and to avoid such a result I provide a safety valve 65 by means of which the pressure and consequently the heat supplied to the reservoir 25 and the tank 35 between the rolls may 115 be regulated, a gage 66 being located for use in regulating the safety valve 65.

While I have shown and described herein in a preferred form of apparatus embodying my invention, this may be altered to a greater or lesser degree without departing from the spirit and intent of the invention.

I claim—

1. In a machine for forming drinking cups, folding mechanism including means 125 for applying an adhesive, a mechanism to receive said cups after the folding operation and including a pair of rotating pressure rolls forming opposite walls of a tank between them to receive a heating medium in 130

liquid form, end walls for said tank, and means for heating said liquid medium.

2. In a machine for forming drinking cups, folding mechanism including means for applying an adhesive, a mechanism to receive said cups after the folding operation and including a pair of rotating pressure rolls forming opposite walls of a tank between them to receive a heating medium in liquid form, end walls for said tank, and means for heating one of said rolls.

3. In a machine for forming drinking cups, folding mechanism including means for applying an adhesive, a pair of rotating rolls forming opposite walls of a tank between them to contain a heating medium in the form of a liquid, end walls for said tank, means for heating said liquid, and means for pressing the rolls one against the other.

4. A machine for forming drinking cups including folding mechanism with means for applying an adhesive, a pair of rotating rolls positioned to constitute opposite walls of a tank between them to contain a heating medium in the form of a liquid, end walls for said tank, a covering of yielding material applied to one of said rolls, and means for heating said liquid.

5. In a machine for forming drinking cups, folding mechanism including means for applying an adhesive, a sterilizing tank

including a pair of rolls located to constitute opposing walls thereof, flanges upon said rolls, each flange projecting beyond the side of the opposite roll to form end walls for said tank, and means for rotating the rolls.

6. In a machine for forming drinking cups, folding mechanism, mechanism to receive said cups after the folding operation and including a pair of rotating pressure rolls positioned to constitute opposite walls of a tank between them to receive a heating medium in liquid form, and flanges upon said rolls each flange projecting beyond the side of the opposite roll to constitute end walls for said tank.

7. In a machine for forming drinking cups, folding mechanism including means for applying an adhesive, mechanism to receive said cups after the folding operation and including a pair of rotating pressure rolls located to form opposite walls of a tank between them, flanges upon said rolls, each flange projecting beyond the side of the opposite roll to form end walls for said tank, and means for delivering the cups from the folding mechanism into said tank.

HENRY B. COOLEY.
